Primary Examiner — Susan E Krakower*Assistant Examiner* — Andrew Kerr*(74) Attorney, Agent, or Firm* — Stevens & Showalter LLP(57) **CLAIM**

The ornamental design for a container base, as shown and described.

DESCRIPTION

FIG. 1 is a front perspective view of a first embodiment of a container base, showing our new design;
 FIG. 2 is a rear perspective view thereof from below;
 FIG. 3 is a top plan view thereof;
 FIG. 4 is a bottom plan view thereof;
 FIG. 5 is a front elevation view thereof;
 FIG. 6 is a rear elevation view thereof;
 FIG. 7 is a left side elevation view thereof;
 FIG. 8 is a right side elevation view thereof;
 FIG. 9 is a front perspective view of a second embodiment of a container base, showing our new design;
 FIG. 10 is a rear perspective view thereof from below;
 FIG. 11 is a top plan view thereof;
 FIG. 12 is a bottom plan view thereof;
 FIG. 13 is a front elevation view thereof;
 FIG. 14 is a rear elevation view thereof;
 FIG. 15 is a left side elevation view thereof; and,
 FIG. 16 is a right side elevation view thereof.

1 Claim, 8 Drawing Sheets(56)
